UNITED STATES PATENT OFFICE.

VINCENT G. APPLE, OF DAYTON, OHIO, ASSIGNOR TO THE APPLE ELECTRIC COMPANY,
OF DAYTON, OHIO, A CORPORATION OF OHIO.

DESIGN FOR A DYNAMO-CASING.

46,306.

Specification for Design.

Patented Aug. 25, 1914.

Application filed April 8, 1914. Serial No. 830,545. Term of patent 14 years.

To all whom it may concern:

Be it known that I, VINCENT G. APPLE, a citizen of the United States, residing at Dayton, in the county of Montgomery, State of Ohio, have invented a new, original, and ornamental Design for Dynamo-Casings, of which the following is a specification, reference being had to the accompanying drawing, forming parts thereof.

Figure 1 is a perspective view showing

my new design for a dynamo casing, and; Fig. 2 is a side elevation thereof.

I claim:

The ornamental design for a dynamo casing, as shown.

VINCENT G. APPLE.
